EXHAUST PIPE ATTACHMENT
 Robert E. Lee, Rte. 1, Larimore, N. Dak.
 Filed Apr. 12, 1960, Ser. No. 21,776
 3 Claims. (Cl. 98—60)

The present invention relates to internal combustion engine exhaust pipes, generally speaking, such as are currently and commonly used on tractors, farm combines and out-of-doors engines wherein, as is generally the case, vertical or substantially vertical pipes are involved.

More particularly, it has reference to such structural adaptations in this field of endeavor where provision is made to guard against the likelihood of extraneous matter, rain, snow and ice getting into the engine by way of an uncovered exhaust conduit.

Inventions in the field of endeavor under consideration, while construed in the broad sense that they are exhaust pipes, also pertain, in a manner of speaking, to mufflers and perhaps, exhaust manifolds. The means currently associated with the discharge end of the exhaust pipe is customarily an attachment of one form or another. In fact, a survey in the art would bring to light protector-type attachments sometimes referred to as closure attachments, guards, shields and so on. Inasmuch as drivers and operators of tractors cannot always be relied upon to voluntarily take precautionary measures it has been repeatedly observed that they either neglect or forget to cover the upper end of the upstanding exhaust pipe despite the fact that it is quite frequently only necessary to use an inverted tin can, a piece of canvas or some make-shift means which is usually carried for such purposes. In any event, and for these and other reasons, many and varied styles and forms of upright exhaust pipe guards have been patented and offered for use and also to discourage using make-shift contrivances.

An object in the instant matter is to structurally, functionally and otherwise improve upon prior art attachments and adaptations by employing a structurally unique device which is characterized by means to be capped over the upper end of the exhaust pipe and which in addition embodies a supplemental cup-like trap with suitable drainage means at the bottom to overcome accumulation of undesirable foreign material which, if it entered the engine by way of the exhaust pipe, would damage the same and greatly interfere with ready starting and reliable operation.

Two embodiments or forms of the invention are contemplated. One is a simple attachment characterized by an elbow with one end of the elbow attachable to the upper end of the exhaust pipe and the other end of the elbow carrying the trapping and draining cup.

The other form of the invention, instead of using an elbow, has to do with an elongated attaching branch or section, and a supplemental parallel cup-like section with the two sections joined by walls and thus providing a construction which may be properly construed as an exhaust pipe with an offset rain trapping and disposal muffler.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a view in side elevation showing a fragmentary portion of a farming tractor or equivalent vehicle with an upright exhaust pipe and illustrating the elbow-type cap constituting one embodiment of the invention;

FIG. 2 is a top plan view on a larger scale with but a minimal portion of the tractor disclosed;

2

FIG. 3 is a section on the vertical line 3—3 of FIG. 2 looking in the direction of the arrows;

FIG. 4 is a view in side elevation showing an exhaust pipe and the aforementioned offset muffler construction which is constructed as an entity and which is applied similarly to a readily applicable and removable attachment;

FIG. 5 is a section on the horizontal line 5—5 of FIG. 4;

FIG. 6 is a detail section on the line 6—6 of FIG. 5; and

FIG. 7 is a view in side elevation of a modified form of the elbow type cap disclosed in FIGS. 1 to 3, inclusive.

In FIGS. 1 and 2 the reference character A designates the tractor or other equivalent vehicle, machine or engine under consideration which is equipped with an upright exhaust pipe B commonly uncovered and therefore subject to giving tractor users and others considerable trouble, that is, unless habitual care in covering the discharge of the exhaust pipe is constantly observed. In the cap-type attachment (see in FIGS. 1 to 3) the attachment comprises two components; namely, an elbow 8, which is the cap, and a trapping and drainage cup 10. These components are integrated in the manner shown and are preferably made from sections of pipe or tubing. The elbow has a lower end portion 12 which is attachable telescopically and removably to the exhaust pipe B. The intermediate bent portion or bend 14 offsets the end portion 16 which is attached to the wall 18 of the cup 20 by way of the opening 22. The connection is preferably made between the open upper end 20 and the substantially closed bottom 23. At the bottom a suitable orifice 24 in the side wall provides a satisfactory drain hole.

This offset cap construction is a simple, practical and economical accessory. It will be made in different sizes and perhaps slightly varied in shape and of appropriate materials to adapt it to serviceable and reliable use. When in position, as shown, in case it should rain or snow, the moisture will be trapped in the cup and gradually drained off and thus disposed of. The cup also serves to trap other foreign material, which if allowed to get into the engine, would be dangerous and damaging.

With respect now to the modification (FIGS. 4, 5 and 6), this particular attachment is referred to as an offset muffler construction. The vehicle is denoted by the reference character A' and the exhaust pipe at B'. The offset muffler is designated generally by the numeral 26 and it is of sheet metal or the like and has two supplemental sections which might perhaps be treated as companion branches 28 and 30. Actually, the section 28 is a tube or length of pipe which has its upper end suitably closed at 31 and this section is capped over the exhaust pipe as shown. The other section 30 is an elongated cup which is open at the top as at 32. At the bottom (FIG. 6) it is provided with a notch or discharge hole 34 cooperable with a port 36 in a cap-like cover 38 which is mounted rotatably and provides a drainage valve. In other words, this closure 38 may be opened and closed at will. The median portions of the respective pipe or tube components 28 and 30 are joined by a communicating chamber which is denoted at 40 in FIG. 5. This chamber embodies a pair of spaced parallel side walls 42 and top and bottom walls 44 and 46 which, considered together, provide a junctional box-like compartment or chamber with the opposed portions thereof communicating with the tube components 28 by way of openings or notches 48 and 49, as seen in FIG. 5.

Generally, it is believed that in both embodiments of the invention a guard-like cap, which may be said to be closed to the atmosphere, is provided and is telescopically and removably applied in the manner shown and described. This cap, in turn, has communicating connection

in both instances with an open-top-trap or cup, said cup being provided with drainage means at the bottom.

It is also to be pointed out that both the offset exhaust cap and offset muffler construction will be preferably built to conform with such "oversize dimensions" as the manufacturer decides on. In fact, preliminary experience tends to show that unless oversize proportions are resorted to undesirable back pressure may interfere with free discharge of gases under pressure.

It may be added that actual experimental use of an offset muffler like that herein disclosed tends to show that the invention will prove out to be highly satisfactory from the standpoint of efficiency, durability and over-all helpful performance.

With reference now to FIG. 7, the slight modification has to do with the aforementioned elbow 8A here having a lower end portion 12A, an intermediate portion 14A, and an upper end portion 16A communicatively joined with centrally apertured portion 22A on the trapping and drainage cup 10A. The cup has a drainage hole 24A at the bottom and the upper portion 20A is open to trap rain, snow and the like. Actually, the only difference here is the fact that the cup 10A instead of being at right angles to the branch 16A is at an inclined or an oblique angle. It is submitted that this pitched or slanted construction provides a more efficient trap.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An attachment for an open upper end of an internal combustion engine exhaust pipe, said attachment comprising a pair of fixedly connected, parallel vertical tubes of similar dimensions and having communication with each other, one end portion of each of said tubes extending longitudinally beyond the corresponding end of the other of said tubes, and closure caps on the inner ends of the tubes, the lowermost cap having a drain port therein, 10 the outer ends of said tubes being open and at least one of said outer ends being telescopically engageable on the upper end of an upstanding exhaust pipe for removably mounting the attachment thereon in communication therewith, said tubes being spaced from each other and having 15 opposed openings in intermediate portions thereof, and a connecting chamber for the tubes extending therebetween and communicating with the openings.
2. An exhaust pipe attachment in accordance with claim 1, said connecting chamber being vertically elongated and 20 including flat, opposed side walls and flat, opposed top and bottom walls.
3. An exhaust pipe attachment in accordance with claim 2, said connecting chamber being spaced from said inner and outer ends of said tubes.
